CLAIM

The ornamental design for an oral-motor therapy pendant substantially as shown and described.

DESCRIPTION

FIG. 1 is a top, front, left perspective view of an oral-motor therapy pendant, showing my new design;

FIG. 2 is a top, back, right perspective view thereof;

FIG. 3 is a front side elevation view thereof;

FIG. 4 is a back side elevation view thereof;

FIG. 5 is a right side elevation view thereof;

FIG. 6 is a left side elevation view thereof;

FIG. 7 is a top plan view thereof; and,

FIG. 8 is a bottom view thereof.

The portions shown in broken lines form no part of the claimed design.

1 Claim, 4 Drawing Sheets(56)
